SEWING MACHINE ATTACHMENT

Lawrence W. Sumegi, Cleveland, Ohio

Application April 7, 1951, Serial No. 219,821

4 Claims. (Cl. 112—137)

1

This invention relates to a device for attachment to the bedplate of a sewing machine for use in connection with a strip or tape of material which is to be fed into contact with the edge of material which is to be bound by the tape and fed to the presser foot and stitching mechanism of the sewing machine.

In the use of a device of this character the tape material, either in spool form or otherwise, is supported or mounted at a convenient place and the strip or tape material usually must be fed so as to turn an angle in order to be in position to be engaged by the material to be bound and subsequently fed to the presser foot and stitching mechanism of the sewing machine.

The present attachment, which may be adjustably attached to the bedplate of a sewing machine, operates upon strip material from a spool or other source which is not shown in the drawing, guides the strip material and performs the strip material so as to fold it essentially along a median line, providing a form over which the folded strip of material may pass with its open edges toward the outside or toward that position with respect to the apparatus which will make it accessible for the introduction of the edge of the material to be bound and, at the same time, to support the strip material so that at the time of presentation of the edge of the material to be bound, a firm engagement between the edge of the material to be bound and the folded strip may be effected and maintained in that position as the combined folded strip and material is fed forward to the presser foot and stitcher of the machine.

Reference should be had to the accompanying drawings which form a part of the specification in which:

Fig. 1 is a top plan view showing the attachment and indicating more or less diagrammatically the stitcher device of a sewing machine;

Fig. 2 is a perspective view showing a portion of the attachment, particularly that part wherein the folded tape is introduced into its associated relation with the material, the edge of which is to be bound;

Fig. 3 is a section upon the line 3—3 of Fig. 1;

Fig. 4 is a section along the line 4—4 of Fig. 1;

Fig. 5 is a section in the line 5—5 of Fig. 1; and

Fig. 6 is a section upon the line 6—6 of Fig. 1.

The device comprises what might be termed a frame. This frame consists of an arm 1 which provides an eye or essentially a round portion, such as indicated at 2 in Fig. 1. The frame also has an arm 3 which extends outwardly from the eye portion 2 and to a certain extent parallel with the arm 1.

2

The arm 1 of the frame carries a plate 4 which has a hollow portion indicated at 5 which is provided with an opening through which there extends a set screw 6 so that the relative position of the plate 4 and the arm 5 may be adjusted.

The plate 4 is provided with an opening adapted to receive a screw 7 by which the plate 4 may be attached to the bedplate of the sewing machine, and the plate 4 also has an arcuate slot 8 adapted to receive a screw 9 which will be secured in an opening in the machine bedplate. Therefore, it will be apparent that the frame as a whole may be adjusted by virtue of manipulation of the screws 6 and 9 so as to position the frame properly with respect not only to receiving the strip of material which is to be folded, but also to positioning the attachment so that when the folded strip is brought into association with the edge 10 of the material to be bound it will be in a straight line position with respect to the presser foot and stitching mechanism of the sewing machine.

This frame which has been described has an angular arm 10 which extends toward the forward part of the attachment and carries a V-shaped trough member 11, the function of which will be later described.

The source of the strip material 12 is not shown, but as before stated, the strip material or tape may be taken from a spool or other support which may be conveniently arranged.

The arm 3 of the attachment has a guiding member 13 and also a guiding member 14 which are arranged in spaced relation. The guides each have a rounded opening substantially of the curvature indicated by the section of the strip material 12 which is shown in the right hand portion of Fig. 1 of the drawing. The tape when passing through the member 13 is guided and partially formed into what might be called a rounded position as indicated at the right-hand portion of Fig. 1 and then when it passes through the guide 14 it has been essentially completely folded upon its median line.

Supported upon the arm 3 is a bracket 15 which rigidly supports one end of a curved bar or form 16 which may be more clearly seen in Fig. 2. This bar is curved so that it is essentially right angular in form. This bar is provided with a slot 17 which extends entirely through the bar, this slot being for the reception of the edge of the material which is to be bound, which material is indicated at 18 in Fig. 1. The upper portion of the bar formed by the slot 17, which upper portion is indicated at 19 is shortened,

while the under portion of the bar is extended as indicated at 20 and this portion of the bar extends within the confines of an essentially V-shaped member 11, all of which is illustrated in Fig. 2.

The eye portion 2 of the support has mounted therein a stub shaft or spindle 22, this shaft being held in position by means of the nut 23. Rotatably mounted upon the stub shaft 22 is a wheel or rotatable member 24, the edge surface of which has a re-entrant angle which is indicated at 25 in the cross-sectional view of Fig. 3.

The wheel or rotatable member 24 is mounted upon stub shaft 22 and the diameter of the opening in the wheel is slightly greater than the diameter of the stub shaft 22, therefore when the wheel is assembled upon the stub shaft 22 there is a slight amount of play between the shaft and the member 24. It sometimes happens that there is an uneven spot or place upon the tape which is being supplied, often due to the fact that as a spool of tape is used up, the end of the tape is attached to the leading end of a new spool of tape and so creates a slight hump or bulge in the tape and then it may happen that there is a spot or bulge due to unevenness in the weaving of the tape. In any event, when such a spot or bulge, in the process of its passing through the device, reaches the portion thereof where it would contact with the rotatable member 24, the fact that the rotatable member has a slight play will prevent any tendency of the tape to "run off" of the rotatable member.

The curved portion of split bar 16 and wheel 24 are so relatively mounted that the bar extends at least in part between the side walls of the V-shaped portion 25.

The movement of the tape or strip may now be traced as it passes to and is acted upon by the attachment which has been described. The tape 12 first passes through the guide member 13 which gives it a preshape which may be described as rounded, or a preliminary step toward the complete folding of the strip. The strip then passes through the guide 14 and in passing through this guide, the folding of the strip along its median line is essentially completed. The strip then passes into contact with what may be described as the rear surface of the guide 16 and will of course pass into the groove 25 of the wheel 24, this being illustrated more particularly in Fig. 3 so that the tape as it moves forward is in contact with the inner portion of the guide 16 and the V-shaped portion of the wheel 24.

At this stage, the edge of the material which is to be bound has been introduced through the slot formed in the member 16 and the edge of the material will be guided into contact with the fold of the tape and will move forward with the tape as the material moves toward the presser foot and stitching mechanism of the machine.

In order to properly guide the tape and properly retain it against the edge of the material to be bound after it has passed from beyond contact with the guide 16 and the V-shape surface of the wheel 24, the member 11 is provided, and in order to guide the tape properly into position in this member 11 the bar 16 is provided with the extension 20 to which reference has already been made. This member 11 may be described as provided with walls which form a V-shape so that in contact with the material to be bound the edges of the tape are definitely retained in folded condition and in contact with the material to which

the tape is to be attached as shown in Fig. 5. The material with its binding stitched thereon is shown in Fig. 6.

The attachment as thus described is very effective in performing the strip or tape, guiding it into position to engage with the edge of the material to be bound, providing an arrangement involving a rotating part which bears against the tape so that there is no tugging or distortion of the tape, but permitting it to freely move around the form which has provision for receiving the edge of the material which is to be bound and finally preserving that relationship so that the material with the binding tape placed thereon is definitely positioned properly, to be operated upon by the presser foot and stitching mechanism of the sewing machine.

It will be apparent that modifications of the mechanism which are herein shown for equivalent purpose and function may be made without departing from the spirit of the invention and within the terms of the claims annexed hereto.

Having thus described my invention, I claim:

1. A binding attachment for use with sewing machines comprising supporting means adapted to be attached to a portion of the sewing machine, rounded guide members carried by said support and adapted to receive strip tape from a source of supply, a bar mounted upon said supporting means, one end of said bar being adjacent to the guiding means and adapted to receive the partially folded tape coming from the guiding means, the said bar having an arcuate portion therein, a wheel member mounted upon said supporting means and arcuately corresponding with the arcuate portion in the bar, whereby the tape passing over the bar passes between the wheel and the bar, said bar being provided with a transverse slot adapted to receive the edge of the material to be bound thereby to introduce the same into contact with the folded tape.

2. A sewing machine attachment for use with sewing machines, comprising supporting means adapted to be attached to a portion of the sewing machine, guiding means having rounded openings which are carried by said support and adapted to receive strip tape from a source of supply, an elongated guiding form mounted upon the said support one end of which is located adjacent the beforementioned guides, said guiding form having an arcuate shaped portion, a rotatable member mounted upon said supporting means the peripheral portion of which is grooved and is mounted upon the supporting means to cooperate with the arcuate portion of the guiding form, the tape received upon the said guiding form being caused to pass between the guiding form and the said rotatable member, the said guiding form being provided with a transversely extending slot which is adapted to receive the edge of the material to be bound and to introduce it within the folded tape passing between the said form and the rotatable member.

3. A binding attachment for use with sewing machines comprising a supporting means adapted to be attached to a portion of the sewing machine, guide members mounted upon said supporting means adapted to receive and incipiently fold tape received from an extraneous source of supply, an elongated guiding form mounted upon the said supporting means and having one end thereof adjacent the aforesaid guiding means whereby the tape passing from the guiding means passes over the said form, the

said guiding form having a bent arcuate shaped portion, a rotatable pulley-like member mounted upon the said supporting means which member has a grooved periphery which cooperates with the arcuate portion of the guiding form, so that the tape passing along the said guiding form passes between said pulley-like member and the guiding form, the said guiding form being provided with a transverse slot at the arcuate portion of said guiding form, the said slot being adapted to receive the edge of the material to which the binding is to be attached.

4. A binding attachment for use with sewing machines comprising a supporting means adapted to be attached to a portion of the sewing machine, guide members mounted upon said supporting means adapted to receive and incipiently fold tape received from an extraneous source of supply, an elongated guiding form mounted upon the said supporting means and having one end thereof adjacent the aforesaid guiding means whereby the tape passing from the guiding means passes over the said form, the said guiding form having a bent arcuate shaped portion, a rotatable pulley-like member mounted upon the said supporting means which member has a grooved periphery which cooperates with

10
